UNITED STATES PATENT OFFICE.

ABEL MAGRI AND ARTHUR V. GRIFFETH, OF PORT WASHINGTON, NEW YORK.

VULCANIZER.

1,156,793.

Specification of Letters Patent.

Patented Oct. 12, 1915.

Application filed October 26, 1914. Serial No. 868,710.

To all whom it may concern:

Be it known that we, ABEL MAGRI, a citizen of Switzerland, and residing at Port Washington, in the county of Nassau and State of New York, and ARTHUR V. GRIFFETH, a citizen of the United States, residing at Port Washington, in the county of Nassau and State of New York, have invented certain new and useful Improvements in Vulcanizers; and we do declare the following to be a full, clear, and exact description of the invention, such as will enable others skilled in the art to which it appertains to make and use the same.

15 Our invention relates to improvements in vulcanizing devices and has for its main object to provide an extremely simple device having a fire pot which performs not only the function of heating the vulcanizing material and the tube but also acts as one member of a clamp for securing the tube in position to be repaired.

20 In carrying out the above end, a further object is to provide structure which will be expanded by the heat generated from the fire pot and to locate this structure at such a point as to cause the expansion thereof to force the combined clamp member and fire pot into binding contact with the article being repaired.

Yet another object is to provide a number of interchangeable fire pots of different sizes, thereby allowing small patches to be applied without the necessity of heating a comparatively large area of the tire and also allowing a comparatively large patch to be applied.

With the above and minor objects in view, the invention resides in certain novel features of construction and combination herein described and claimed and shown in the drawings wherein;

Figure 1 is a side elevation of our improved vulcanizer showing a comparatively small fire pot clamped in active position upon a tube; Fig. 2 is a transverse section taken on the line 2—2 of Fig. 1; Fig. 3 is a top plan view of a comparatively large fire pot, and Fig. 4 is a vertical transverse section as seen on the line 3—3 of Fig. 3.

In the accompanying drawings, the numeral 1 designates a suitably constructed base block which is designed to be clamped in a horizontal position upon a suitable horizontal board B which may be the top of a work bench, a table, or the running board

of an automobile, a clamp C, of ordinary construction being provided for this purpose. Rising from the base block 1 and secured thereto by a bolt or screw 2, is an inverted L-shaped bracket 3 whose horizontal arm is provided with an integral nut 4 which receives a crank operated screw 5.

Designed to be positioned upon a tube T, is a comparatively small fire pot 6 and a relatively large pot 6', the pot 6 being here shown as cup-shaped and as having an upright post 7 rising from its center, the upper end of said post being provided with a recess 8 designed to receive the lower end of the screw 5, while the lower end of said post 7 is enlarged as seen at 9 whereby to provide an indicator for determining the proper amount of liquid fuel to be placed within the pot. The fire pot 6' is provided with an upright central post 7' having a recess 8' in its upper end, said post being braced by a plurality of webs 10 which radiate therefrom and which rise from the bottom of said pot. These ribs not only act as bracing ribs, but coact with a plurality of upright pins or posts 11 to conduct heat to the bottom of the pot. The posts 11 may be enlarged at their lower ends as indicated at 9' for determining the proper amount of fuel to be employed.

With the parts as above described, the tube T is provided with the usual patch P to be vulcanized thereto, one of the fire pots is positioned upon the patch as clearly seen in Figs. 1 and 2 and the screw 5 is moved downwardly until its lower end seats within the recess formed in the central post of the fire pot, said pot being then partially filled with fuel which is ignited. It will therefore be seen that said pot acts not only as heating means for vulcanizing the patch P to the tube T, but acts as one section of the clamp, the other section being here shown in the form of the base block 1. As the burning fuel within the fire pot heats the same and melts the patch P, the screw 5 and post 7 or 7', as the case may be, are expanded, this expansion now forcing the combined fire pot and clamping member into for'able contact with the tube and the patch thereon. It has been found, by actual experience, that the device operating as above described, will vulcanize more perfectly than the ordinary type of vulcanizers since the proper amount of pressure is exerted upon the heated patch, it being understood that said patch flattens out as it is heated and

that more pressure is necessary in order to force the same into contact with the tube. This increased pressure, it will be noted, is applied absolutely automatically and to the proper extent.

Another important feature, is the fact that no unnecessary material is heated, but only that being patched, and that the pressure on the heated patch gradually increases as the temperature of the patch rises, thereby assuring the greatest amount of pressure at the time the patch is in the most molten state, the effect being a perfect patch.

Having thus described our invention, what we claim as new and desire to secure by Letters Patent is:

A vulcanizer comprising a flat horizontal rectangular base plate, a clamp for securing one end thereof to a horizontal support, an

inverted L-shaped bracket having at its 20 lower end a foot secured to the upper side of the base plate at the intermediate portion thereof, a rigid nut carried by the other end of said bracket and having an upright axis, a fire pot between the nut and the base plate 25 having a central post provided in its upper end with a cavity, and a clamping screw threaded through the nut and having its lower end received by the aforesaid cavity.

In testimony whereof we have hereunto set our hands in presence of two subscribing witnesses.

ABEL MAGRI.
ARTHUR V. GRIFFETH.
